UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Original application filed March 9, 1920, Serial No. 364,458. Divided and this application filed August 17, 1922. Serial No. 582,504.

To all whom it may concern:

Be it known that I, LLOYD V. LEWIS, a citizen of the United States, residing at Edgewood Borough, in the county of Allegheny and State of Pennsylvania, have invented certain new and useful Improvements in Railway-Traffic-Controlling Apparatus, of which the following is a specification.

10 My invention relates to railway traffic-controlling apparatus of the type wherein automatic brake application mechanism on a train or vehicle is controlled by energy which is supplied thereto from the trackway.

15 The present application is a division of my copending application filed on the 9th day of March, 1920, Serial No. 364458, for railway traffic controlling apparatus.

20 I will describe one form of apparatus embodying my invention, and will then point out the novel features thereof in claims.

25 In the accompanying drawings, Fig. 1 is a diagrammatic view showing one form of trackway apparatus adapted for co-operation with vehicle carried apparatus embodying my invention. Fig. 2 is a view showing one form of vehicle carried apparatus embodying my invention.

30 Similar reference characters refer to similar parts in each of the views.

Referring first to Fig. 1, the reference characters 1 and 1^a designate the track rails of a railway along which traffic normally moves in the direction indicated by the arrow, and which rails are divided by insulated joints 2 to form a plurality of successive blocks A—B, B—C, etc. Located adjacent the entrance end of each block is a roadside signal which is designated by the reference character S with an exponent corresponding to the location. Each of these signals, as here shown, is of the semaphore type, adapted to indicate "stop", "caution" and "proceed", according as the semaphore is in the horizontal, the inclined or the vertical position. The apparatus for controlling the signals is omitted from the drawing for the reason that it forms no part of my invention, but it is understood that in accordance with usual practice each signal indicates "stop" when the corresponding block is occupied, "caution" when the corresponding block is unoccupied and the

block next in advance is occupied, and "proceed" when the corresponding block and the block next in advance are unoccupied. Thus, as shown in the drawing, the block to the right of point D is occupied by a vehicle V, so that signal S^b for this block indicates "stop", signal S^c indicates "caution", and signal S^b indicates, "proceed".

Each block is provided with means for connecting a source of alternating vehicle governing current across the track rails adjacent the exit end of the block. As here shown, this is accomplished by a transformer for each block, designated by the reference character T with an exponent corresponding to the location, the secondary of which is constantly connected across the rails of the block, and the primary of which is at times connected with a transmission line E which is supplied with vehicle governing alternating current by a generator F. The primary circuit of each transformer T includes a circuit controller operated by the adjacent signal and designated by the reference character H with the same exponent as that of the signal. Each of these circuit controllers is arranged to be closed when the signal indicates "proceed" or "caution", but open when the signal indicates "stop". It will be seen, therefore, that vehicle governing current is supplied to the rails of a block when the signal for the block next in advance indicates "proceed" or "caution", but not when it indicates "stop". In other words, this current is supplied to each block whenever the block next in advance is unoccupied.

In accordance with usual practice, an impedance 6 is interposed in the connection between one of the track rails and the secondary of each transformer T to limit the current drawn from this transformer when a car or train is near the exit end of the block.

Referring now to Fig. 2, the vehicle carried apparatus, in the form here shown, includes two laminated soft iron cores 9 and 9^a, which are mounted on the vehicle in advance of the forward axle and are located over the two track rails 1 and 1^a, respectively. Each of these cores is substantially U-shaped, with its legs pointing downwardly, and each core is disposed transversely with respect to the rail. The two cores 9 and 9^a are provided with windings

10 and 10^a , respectively. It is apparent, therefore, that when alternating current flows in either rail, part of the magnetic lines of force surrounding such rail will 5 pass through the core which is directly over the rail and so will induce an alternating potential in the coil carried by such core.

The coils 10 and 10^a are included in a receiving circuit a , the coils being so connected 10 in this circuit that the potentials created in the coils by an alternating current flowing in opposite directions in the two rails are additive. It will be seen, therefore, that track circuit current from the transformers 15 T will induce an alternating potential in the receiving circuit a . The potential thus created in the receiving circuit is utilized to control the supply of current to a magnet M^a , suitable amplifying apparatus W preferably being interposed between the receiving circuit and the magnet as indicated in the drawing.

Relay M^a controls two devices 46 and 47 in such manner that each device is energized 25 when relay M^a is closed, and de-energized when relay M^a opens. These devices have different time intervals of operation, and as here shown each device is in the form of a relay, relay 47 being of the slow-releasing 30 type while relay 46 is of the quick-releasing type. It follows that when relay M^a opens, relay 46 will open at once, but relay 47 will remain closed for a fixed interval of time.

Relays 46 and 47 control a brake application magnet Y which is arranged to cause an automatic application of the brakes when the magnet becomes de-energized. Magnet Y is energized when both relays 46 and 47 are closed and also when both of these relays are open. When the relays are closed, the circuit for magnet Y is from battery 52, through wire 53, upper point of contact 54 of relay 46, wire 62, upper point of contact 55 of relay 47, wires 56, 57, 58, winding of 45 magnet Y , wire 63, contact 64 controlled by magnet Y , and wires 65 and 66 to battery 52. When relays 46 and 47 are open, the circuit for magnet Y is from battery 52, through wire 53, lower point of contact 54, 50 wire 59, contact 60, wires 61 and 58, winding of magnet Y and thence as before to battery 52. It will be seen from the foregoing that when relay M^a opens, the circuit for magnet Y will at once be opened at contact 54 of 55 relay 46, but that after a fixed interval of time, determined by the time characteristic of relay 47, magnet Y may again be energized by the operation of push button 67 and the magnet will then remain energized 60 as long as relay M^a is open. Push button 67 merely closes a shunt around the magnet operated contact 64.

In order to prevent an automatic application of the brakes when relay M^a opens, 65 I have provided means for energizing mag-

net Y temporarily independently of relay contacts 54, 55 and 60. This means comprises a contact 68 controlled as hereinafter explained and connected in shunt with the contacts of relays 46 and 47. When circuit controller 68 is closed, the circuit for magnet Y is from battery 52, through wire 69, circuit controller 68, wires 70, 57 and 58, winding of magnet Y , wire 63, contact 64, and wires 65 and 66 to battery 52.

Circuit controller 68 is operated by a piston 71 moving in a cylinder 72. The piston 71 is biased to its uppermost position by a spring 73, and when in this position circuit controller 68 is open. The piston 71 may be moved downwardly, however, in opposition to the action of the spring 73, by applying fluid pressure to the upper end of cylinder 72, and when this occurs circuit controller 68 is closed. Fluid pressure is supplied to the upper end of cylinder 72 by a reservoir R^4 which is at times connected with main reservoir through pipe 8^c, and at other times with the upper end of cylinder 72 through pipe 74, the connections just mentioned being accomplished by a manually operable valve Q' . This valve Q' normally occupies the position shown in the drawing so that reservoir R^4 is normally charged with main reservoir pressure. When it is desired to suppress an automatic application of the brakes, valve Q is swung in clockwise direction, so that reservoir R^4 is connected with the upper end of cylinder 72 whereupon piston 71 is moved downwardly to close circuit controller 68. The air in reservoir R then flows out through an orifice 75 of restricted area, so that after a fixed interval of times, such for example, as 15 to 20 seconds, piston 71 returns to its initial position under the influence of spring 73.

The operation of the apparatus shown in Fig. 2 is as follows:

When the vehicle passes a caution signal, relay M^a opens, so that unless the engineer takes suitable action magnet Y becomes de-energized to cause an automatic application of the brakes. If, however, valve Q' is reversed just prior to the opening of relay M^a , magnet Y remains energized during the interval of time required for the contacts of relay 47 to reverse, so that this magnet is maintained in energized condition until the second circuit for the magnet becomes closed.

It will be observed that when magnet Y is de-energized it cannot again become energized until push button 71 is closed. This push button is preferably located in such position on the vehicle as to require the vehicle to come to rest before the push button can be reached.

It will be observed that if the driver fails to return the valve Q' to its original or normal position, circuit controller 68 will open upon

the expiration of the time interval of 15 or 20 seconds, so that the suppressing function of this circuit controller is then lost and an automatic application of the brakes will occur the next time that relay M^a opens unless the driver operates the valve Q' in the proper manner.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a magnet on a vehicle, apparatus located in the trackway for causing said magnet to be energized while traffic conditions in advance are safe but not when traffic conditions in advance are dangerous, a quick releasing relay and a slow releasing relay controlled by said magnet and each arranged to be de-energized when the magnet becomes de-energized, brake application mechanism controlled by said relays and set into operation during the interval between the opening of the quick releasing relay and the opening of the slow releasing relay, and manually operable means on the vehicle effective to prevent said brake application mechanism being set into operation during said interval.

2. Railway traffic controlling apparatus comprising two relays located on a vehicle and designed to open in different time intervals after de-energization, brake application mechanism controlled by said relays and set into operation during the interval between the opening of the first relay and the opening of the second relay after de-energization of said relays, and means in the trackway for causing said relays to be energized under safe traffic conditions but not under unsafe traffic conditions.

3. Railway traffic controlling apparatus comprising two relays located on a vehicle and designed to open in different time intervals after de-energization, brake application mechanism controlled by said relays and set into operation during the interval between the opening of the first relay and the opening of the second relay after de-energization of said relays, manually operable means on the vehicle for preventing said brake application mechanism from being set into operation during said interval, and means in the trackway for causing said relays to be energized under safe traffic conditions but not under unsafe traffic conditions.

4. Railway traffic controlling apparatus comprising two relays located on a vehicle

and designed to open in different time intervals after de-energization, brake application mechanism on the vehicle, means controlled by said relays for holding said mechanism in inactive condition when both relays are open, said means operating to set said mechanism into operation during the interval between the opening of the first relay and the opening of the second relay after de-energization of the relays, and means in the trackway for causing said relays to be energized under safe traffic conditions but not under unsafe traffic conditions.

5. Railway traffic controlling apparatus comprising two vehicle carried devices having different time intervals of operation, brake application mechanism controlled by said devices and set into action during the interval between the operations of said devices, manually operable means on the vehicle for preventing operation of said brake application mechanism during said interval, and means controlled from the trackway for initiating the operations of said devices upon a change from a more favorable to a less favorable traffic condition.

6. Railway traffic controlling apparatus comprising two vehicle carried devices having different time intervals of operation, brake application mechanism on the vehicle, means controlled by said devices for holding said mechanism in inactive condition before the operation of said devices has been initiated and also after the operation of both devices has been completed, but for setting said mechanism into action during the interval between the operations of said devices, and means controlled from the trackway for initiating the operations of said devices upon a change from a more favorable to a less favorable traffic condition.

7. Railway traffic controlling apparatus comprising two vehicle carried devices having different time intervals of operation, brake application mechanism on the vehicle, means controlled by said devices for holding said mechanism in inactive condition before the operation of said devices has been initiated and also after the operation of both devices has been completed, but for setting said mechanism into action during the interval between the operations of said devices, manually operable means on the vehicle for preventing operation of said brake application mechanism during said interval, and means controlled from the trackway for initiating the operations of said devices upon a change from a more favorable to a less favorable traffic condition.

8. Railway traffic controlling apparatus comprising a comparatively quick releasing relay and a comparatively slow releasing re-

lay located on a vehicle, means in the track-way for causing energization of said relays and for permitting both relays to become de-energized in response to change 5 from a more favorable to a less favorable traffic condition, a brake application magnet on said vehicle having an armature contact closed when the magnet is energized, a circuit for said magnet including said 10 armature contact and a front contact of each of said relays in series, a second circuit for said magnet including said armature contact and a back contact of each of said relays in series, and a normally 15 open manually operable circuit controller on said vehicle connected in both of said circuits in multiple with the armature contact of said magnet.

9. Railway traffic controlling apparatus 20 comprising a comparatively quick releasing relay and a comparatively slow releasing relay located on a vehicle, means in the track-way for causing energization of said relays and for permitting both relays to become 25 de-energized in response to change from a more favorable to a less favorable traffic condition, a brake application magnet on said vehicle, and a control circuit for said magnet including a front contact of each of 30 said relays.

10. Railway traffic controlling apparatus comprising a comparatively quick releasing relay and a comparatively slow releasing relay located on a vehicle, means in the track-way for causing energization of said relays and for permitting both relays to become de-energized in response to change from a more favorable to a less favorable traffic condition, a brake application magnet on said vehicle and a control circuit for said magnet including a front contact of each of said relays and an armature contact closed only when said magnet is energized.

11. Railway traffic controlling apparatus 45 comprising a comparatively quick releasing relay and a comparatively slow releasing relay located on a vehicle, means in the track-way for causing energization of said relays and for permitting both relays to become 50 de-energized in response to change from a more favorable to a less favorable traffic condition, a brake application magnet on said vehicle, a control circuit for said magnet including a front contact of each of said 55 relays, and a branch for said circuit around said front contacts and including a back contact of each relay.

12. Railway traffic controlling apparatus 60 comprising a comparatively quick releasing relay and a comparatively slow releasing relay located on a vehicle, means in the track-way for causing energization of said relays and for permitting both relays to become de-energized in response to change from a 65 more favorable to a less favorable traffic

condition, a brake application magnet on said vehicle, a control circuit for said magnet including a front contact of each of said relays, and an armature contact closed only when said magnet is energized, and a branch 70 for said circuit around said front contacts and including a back contact of each relay.

13. Railway traffic controlling apparatus comprising a comparatively quick releasing relay and a comparatively slow releasing relay located on a vehicle, means in the track-way for causing energization of said relays and for permitting both relays to become 75 de-energized in response to change from a more favorable to a less favorable traffic 80 condition, a brake application magnet on said vehicle and a control circuit for said magnet including a front contact of each of said relays and an armature contact closed only when said magnet is energized, 85 and a branch around said armature contact including a normally open manually operable circuit controller.

14. Railway traffic controlling apparatus comprising a comparatively quick releasing 90 relay and a comparatively slow releasing relay located on a vehicle, means in the track-way for causing energization of said relays and for permitting both relays to become de-energized in response to change from a 95 more favorable to a less favorable traffic condition, a brake application magnet on said vehicle and a control circuit for said magnet including a front contact of each 100 of said relays and an armature contact closed only when said magnet is energized, a branch around said front contacts including a back contact of each of said relays, and a branch around said armature contact including a normally open manually operable 105 circuit controller.

15. Railway traffic controlling apparatus comprising a comparatively quick releasing relay and a comparatively slow releasing relay located on a vehicle, means in the trackway for causing energization of said relays and for permitting both relays to become de-energized in response to change from a more favorable to a less favorable traffic condition, a brake application magnet on said vehicle, and a control circuit for said magnet including a front contact of each of said relays, a branch around said 110 relay contacts including a normally open circuit controller, and manually operable 115 means effective for a given interval of time to close said circuit controller.

16. Railway traffic controlling apparatus comprising a comparatively quick releasing 120 relay and a comparatively slow releasing relay located on a vehicle, means in the track-way for causing energization of said relays and for permitting both relays to become de-energized in response to change from a 125 more favorable to a less favorable traffic 130

condition, a brake application magnet on said vehicle and a control circuit for said magnet including a front contact of each of said relays and an armature contact closed only when said magnet is energized, a branch around said relay contacts including a normally open circuit controller, and manually operable means effective for a given interval of time to close said circuit controller.

17. Railway traffic controlling apparatus comprising a comparatively quick releasing relay and a comparatively slow releasing relay located on a vehicle, means in the trackway for causing energization of said relays and for permitting both relays to become de-energized in response to change from a more favorable to a less favorable traffic condition, a brake application magnet on said vehicle, a control circuit for said magnet including a front contact of each of said relays, and a branch for said circuit around said front contacts and including a back contact of each relay, a branch around said relay contacts including a normally open circuit controller, and manually operable means effective for a given interval of time to close said circuit controller.

18. Railway traffic controlling apparatus comprising a comparatively quick releasing relay and a comparatively slow releasing relay located on a vehicle, means in the trackway for causing energization of said relays and for permitting both relays to become de-energized in response to change from a more favorable to a less favorable traffic condition, a brake application

magnet on said vehicle, a control circuit for said magnet including a front contact of each of said relays, and an armature contact closed only when said magnet is energized, and a branch for said circuit around said front contacts and including a back contact of each relay, a branch around said relay contacts including a normally open circuit controller, and manually operable means effective for a given interval of time to close said circuit controller.

19. Railway traffic controlling apparatus comprising a comparatively quick releasing relay and a comparatively slow releasing relay located on a vehicle, means in the trackway for causing energization of said relays and for permitting both relays to become de-energized in response to change from a more favorable to a less favorable traffic condition, a brake application magnet on said vehicle and a control circuit for said magnet including a front contact of each of said relays and an armature contact closed only when said magnet is energized, a branch around said front contacts including a back contact of each of said relays, and a branch around said armature contact including a normally open manually operable circuit controller, a branch around said relay contacts including a second normally open circuit controller, and manually operable means effective for a given interval of time to close said second circuit controller.

In testimony whereof I affix my signature.

LLOYD V. LEWIS.
